UNITED STATES PATENT OFFICE.

HARRY A. DOUGLAS, OF BRONSON, MICHIGAN.

LAMP.

1,256,531.

Specification of Letters Patent. Patented Feb. 19, 1918.

Application filed March 9, 1914, Serial No. 823,365. Renewed December 21, 1916. Serial No. 138,286.

To all whom it may concern:

Be it known that I, HARRY A. DOUGLAS, citizen of the United States, residing at Bronson, in the county of Branch and State 5 of Michigan, have invented a certain new and useful Improvement in Lamps, of which the following is a full, clear, concise, and exact description, reference being had to the accompanying drawings, forming a part of 10 this specification.

My invention relates to reflecting electric lamps and has for one of its objects the provision of an improved mounting for the glass front which is commonly provided for 15 such a lamp. By means of one characteristic of my invention the door or lid which permits access to the interior of the lamp structure operates as a clamping device for holding the glass front against the portion of the 20 lamp structure to the rear of the glass.

In accordance with another feature of my invention the glass front is provided with a resilient mounting that operates to maintain the glass front in its normal position but 25 which will yield to allow the glass momentarily to shift in its own plane and with reference to the balance of the lamp structure when the lamp structure is subject to sufficient shock, whereby fracture of the 30 glass front is prevented. The lid which operates to clamp the glass in position has such pressure upon the glass as to hold the glass in its own plane while at the same time permitting the glass to move in its plane under 35 the circumstances described. The resilient mounting for the glass is desirably carried by the lid.

The invention has as another of its characteristics the provision of an improved 40 means of attaching the lid to the portion of the lamp structure to the rear of the glass.

I will explain my invention more fully by reference to the accompanying drawing showing the preferred embodiment thereof 45 and in which Figure 1 is a sectional elevation on line 1—1 of Fig. 2; Fig. 2 is a sectional elevation on line 2—2 of Fig. 1; Fig. 3 is a plan view on line 3—3 of Fig. 2; and Fig. 4 is a sectional view on line 4—4 50 of Fig. 2.

Like parts are indicated by similar characters of reference throughout the different figures.

The back element *a* of the lamp is desirably formed of sheet metal as is also the 55 reflector portion *b* whose concave surface,

which is the reflecting surface, is suitably brightened for the purpose of reflecting the light which emanates from the incandescent lamp *c*. The front of the lamp is provided 60 with a door or lid *d*, later to be more fully described, for affording access to the interior of the lamp structure. The electric lamp bulb *c* has a base *d'* that carries the lamp terminals, this base being suitably 65 held within a sleeve *f* as by means of a bayonet catch *g*. The back element *a* and the reflector element *b* are in separable relation, the insetting rim *h* of the latter having a sliding fit with the outsetting rim *i* of the 70 former, the extent to which the rim *h* may move inwardly being limited by its engagement with the flaring portion of the back *a* as illustrated in Fig. 1. The back and reflector parts are maintained in the fixed relationship illustrated in Fig. 1 by means of 75 the shell or sleeve *f* which is threaded at its rear there to be engaged by a nut *k* having an enlargement received within a cup formation provided at the back of the element *a*. 80 The shell *f* carries a flange *l* which engages the front face of the reflector *b*, the flange *l* and the nut *k* coöperating to maintain the reflector and the back element *a* in the normal relationship illustrated in Fig. 1. My 85 companion application Serial No. 713,317, filed August 5, 1912, contains claims which cover the structure employing the shell *f*, nut *k*, and flange *l* for the purpose described. The back element *a* carries a socket 90 *m* from which conductors *n* lead to the lamp, and which socket is capable of receiving a terminal plug connected with the source of current which is to supply the lamp.

The door or lid *d* desirably carries three 95 spring hooks *o*, illustrated most clearly in Fig. 4, which are adapted to be projected through slots *p* provided in the flange continuation *q* of the deflector structure *b*, and which flange continuation *q* surrounds the 100 reflector proper and is interposed between the same and the rim *h* of the reflector. When the lid is to be placed in position the hooks *o* are so registered with the slots *p* that the hook ends of the hooks may pass 105 through said slots whereafter the lid may be turned so as to effect engagement of the hooks with the rearwardly extending lugs or ridges *r* that margin the ends of said slots, also as indicated clearly in Fig. 4, 110 the hooks yielding as they ride over the lugs and positioning themselves as indicated in

Fig. 4 by their own resilience when the lid has been sufficiently turned.

The light transmitting cover *s*, preferably of glass, is desirably permanently associated with the lid *d*, to which end the lid carries a number of insetting glass holding clips *t*, which are of strip spring metal, and which are bent to afford grooves for receiving the glass as illustrated most clearly in Fig. 1. 10 For the sake of economy in manufacture, each glass support *t* may be integrally formed of the same piece of strip spring metal with the spring hook *o*. The resilient glass supporting elements *t* operate to maintain the 15 normal position of the glass *s* with respect to the lid *d* but yield, upon sufficient shock, to permit the glass to move slightly in its own plane with respect to the balance of the lamp structure so that the glass will not be fractured. The spring pressure with which 20 the hooks *o* maintain the rear face of the glass *s* against the front of the reflector *b* is not sufficient to prevent the movement of the glass *s* in its own plane when occasion 25 requires, the parts being properly proportioned to make the pressure of the glass *s* upon the reflector *b* sufficiently light for this purpose, though the hooks *o* operate to hold the lid *d* properly in place, these hooks 30 maintaining the outer rims *u* of the lid *d* in firm engagement with the outsetting bead *v* formed in the back element *a*.

While I have herein shown and particularly described the preferred embodiment 35 of my invention, I do not wish to be limited to the precise details of construction shown as changes may readily be made without departing from the spirit of my invention, but having thus described my invention I 40 claim as new and desire to secure by Letters Patent the following:

1. A lamp structure including a back element; a concave reflector in front of the back element; a lamp bulb; a mounting for the 45 lamp bulb which holds the back element and reflector together; a light transmitting cover at the forward end of the reflector; a resilient mounting for the cover that permits the cover to move in its plane; a door engaging 50 the front face of the cover; and spring mechanism for separably coupling the door with a door supporting portion of the lamp structure and exerting pressure upon the 55 cover that permits the cover to move in its own plane.

2. A lamp structure including a back element; a concave reflector in front of the back element; means for holding the reflector and lamp back together; a light transmitting 60 cover at the forward end of the reflector; a resilient mounting for the cover that permits the cover to move in its plane; a door engaging 65 the front face of the cover; and spring mechanism for separably coupling the door with a door supporting portion of the lamp structure and exerting pressure upon the 70 cover that permits the cover to move in its own plane.

the lamp structure and exerting pressure upon the cover that permits the cover to move in its own plane.

3. A lamp structure including a back element; a concave reflector in front of the 70 back element; a lamp bulb; a mounting for the lamp bulb which holds the back element and reflector together; a light transmitting cover at the forward end of the reflector movable in its own plane; a door engaging 75 the front face of the cover; and spring mechanism for separably coupling the door with a door supporting portion of the lamp structure and exerting pressure upon the 80 cover that permits the cover to move in its own plane.

4. A lamp structure including a back element; a concave reflector in front of the back element; means for holding the reflector and lamp back together; a light transmitting 85 cover at the forward end of the reflector movable in its own plane; a door engaging the front face of the cover; and spring mechanism for separably coupling the door with a door supporting portion of the lamp structure and exerting pressure upon the 90 cover that permits the cover to move in its own plane.

5. A lamp structure including a back element; a concave reflector in front of the 95 back element; a lamp bulb; a mounting for the lamp bulb which holds the back element and reflector together; a light transmitting cover at the forward end of the reflector; a resilient mounting for the cover that permits the cover to move in its plane; a door 100 engaging the front face of the cover; and mechanism for separably coupling the door with a door supporting portion of the lamp structure and exerting pressure upon the 105 cover that permits the cover to move in its own plane.

6. A lamp structure including a back element; a concave reflector in front of the back element; means for holding the reflector and lamp back together; a light transmitting 110 cover at the forward end of the reflector; a resilient mounting for the cover that permits the cover to move in its plane; a door engaging the front face of the cover; 115 and mechanism for separably coupling the door with a door supporting portion of the lamp structure and exerting pressure upon the cover that permits the cover to move in its own plane.

7. A lamp structure including a back element; a concave reflector in front of the back element; a lamp bulb; a mounting for the lamp bulb which holds the back element and reflector together; a light transmitting 125 cover at the forward end of the reflector movable in its own plane; a door engaging the front face of the cover; and mechanism for separably coupling the door with a door supporting portion of the lamp structure and exerting pressure upon the 130 cover that permits the cover to move in its own plane.

ture and exerting pressure upon the cover that permits the cover to move in its own plane.

8. A lamp structure including a back element; a concave reflector in front of the back element; means for holding the reflector and lamp back together; a light transmitting cover at the forward end of the reflector movable in its own plane; a door 10 engaging the front face of the cover; and mechanism for separably coupling the door with a door supporting portion of the lamp structure and exerting pressure upon the cover that permits the cover to move in its 15 own plane.

9. A lamp structure including a back element; a concave reflector in front of the back element; means for holding the reflector and lamp back together; a light transmitting cover at the forward end of the reflector; a resilient mounting for the cover that permits the cover to move in its own plane; a door; and spring mechanism exerting pressure upon the cover that permits the 25 cover to move in its own plane.

10. A lamp structure including a back element; a concave reflector in front of the back element; means for holding the reflector and lamp back together; a light transmitting cover at the forward end of the reflector movable in its own plane; a door; and spring mechanism exerting pressure upon the cover that permits the cover to move in its own plane.

35 11. A lamp structure including a back element; a concave reflector in front of the back element; means for holding the reflector and lamp back together; a light transmitting cover at the forward end of the reflector; a resilient mounting for the cover that permits the cover to move in its own plane; a door; and mechanism exerting pressure upon the cover that permits the cover to move in its own plane.

45 12. A lamp structure including a back element; a concave reflector in front of the back element; means for holding the reflector and lamp back together; a light transmitting cover at the forward end of the reflector movable in its own plane; a door; and mechanism exerting pressure upon the cover that permits the cover to move in its own plane.

55 13. A lamp structure including a back element; a concave reflector in front of the back element; means for holding the back element and reflector together; a light transmitting cover at the front end of the reflector; a door having a rim which is in sliding engagement with a rim which is provided upon a door supporting portion of the lamp structure; and spring mechanism for separably coupling the door with the supporting portion of the lamp structure.

65 14. A lamp structure including a back ele-

ment; a concave reflector in front of the back element; a lamp bulb; a mounting for the lamp bulb which holds the back element and reflector together; a light transmitting cover at the front end of the reflector; a door having a rim which is in sliding engagement with a rim which is provided upon a door supporting portion of the lamp structure; and spring mechanism for separably coupling the door with the supporting portion of the lamp structure.

70 15. A lamp structure including a back element; a concave reflector in front of the back element; a lamp bulb; a mounting for the lamp bulb which holds the back element and reflector together; a door which is in sliding engagement with a complementary portion of the lamp structure; and spring mechanism for separably coupling the door with the door supporting portion of the lamp structure.

80 16. A lamp structure including a back element; a concave reflector in front of the back element; a lamp bulb; a mounting for the lamp bulb which holds the back element and reflector together; a door which is in sliding engagement with the lamp reflector; and spring mechanism for separably coupling the door and lamp reflector.

85 17. A lamp structure including a door element; a supporting element for the door; hooks carried by one of said elements and operating separably to secure the door element and door supporting element together, one of said elements being provided with slots through which the hook ends pass; and hook engaging portions at said slots.

90 18. A lamp structure including a door element; a supporting element for the door; hooks carried by one of said elements and operating separably to secure the door element and door supporting element together, one of said elements being provided with slots through which the hook ends pass; and hook engaging ridges at said slots.

110 19. A lamp structure including a back element; a concave reflector in front of the back element; a lamp bulb; a mounting for the lamp bulb which holds the back element and reflector together; a light transmitting cover at the forward end of the reflector; and a mounting for said cover that permits it to move in its own plane with reference to the reflector and back element.

115 20. A lamp structure including a back element; a concave reflector in front of the back element; a lamp bulb; a mounting for the lamp bulb which holds the back element and reflector together; a light transmitting cover at the forward end of the reflector; and a resilient mounting for said cover that permits it to move in its own plane with reference to the reflector and back element.

120 21. A lamp structure including a back element; a concave reflector in front of the

back element; means for holding the reflector and back element in fixed relation; a light transmitting cover at the forward end of the reflector; and a mounting for said cover that permits it to move in its own plane with reference to the reflector and back element.

22. A lamp structure including a back element; a concave reflector in front of the back element; means for holding the reflector and back element in fixed relation; a light transmitting cover at the forward end of the reflector; and a resilient mounting for said cover that permits it to move in its own plane with reference to the reflector and back element.

23. A lamp structure including a door; and spring hooks carried by the door and operating separably to secure the door and the portion of the lamp structure to the rear of the door together, the rear portion of the lamp structure being provided with slots through which the hook ends of the hooks project and lugs margining the slots for engagement with the hooks. 20 25

In witness whereof, I hereunto subscribe my name this 17th day of February, A. D., 1914.

HARRY A. DOUGLAS.
